UNITED STATES PATENT OFFICE.

WALTER J. SPIRO, OF WHITE PLAINS, NEW YORK.

MULTIPLE CIRCUIT SWITCH.

Application filed September 8, 1921. Serial No. 499,123.

To all whom it may concern:

Be it known that I, WALTER J. SPIRO, citizen of the United States, residing at White Plains, in the county of Westchester and State of New York, have invented certain new and useful Improvements in Multiple Circuit Switches, of which the following is a specification.

This invention relates to a multiple circuit switch and particularly to a construction adapted for the convenient control of the electric circuits upon a motor vehicle and involves certain improvements upon the structure disclosed in my application filed September 16, 1920, Serial No. 410,729.

The invention has for an object to provide a novel and improved construction of switch and ease locking means adapted to lock all of the parts, or to leave certain parts free for operation while the remaining parts are locked, through a predetermined adjustment of the mechanism.

Another object of the invention is to present an improved structure of rotatable switch member and cooperating spring actuated contact therefor.

A further object of the invention is to provide a novel construction of horn operating arm disposed beneath and adjacent the hand hold of a steering wheel, and of the contact lever controlled thereby.

Another object of the invention is to produce an improved locking mechanism comprising an adjustably mounted locking plate adapted to cooperate with holding detents for switch members, a locking pin for a horn lever, and locking means upon an opposite member of the casing.

A further object of the invention is to present a new form of casing comprising separable members, one of which carries switch actuating parts and the opposite member provided with circuit contacts co-acting with said parts, together with a locking device upon one member cooperating with locking means upon the other when the case is in closed position.

Other and further objects and advantages of the invention will be hereinafter set forth and the novel features thereof defined by the appended claims.

In the drawings—

Figure 1 is a vertical section of the invention mounted in relation to a steering wheel;

Figure 2 is an elevation of the switch with the casing opened;

Figure 3 is a detail plan of the steering post connection;

Figure 4 is a detail section showing all members locked;

Figure 5 is a similar view with all members locked excepting the light controlling switch;

Figure 6 is a like view with all members locked excepting the horn lever;

Figure 7 is an elevation of the supporting disk upon the lock casing;

Figure 8 is a rear elevation of the locking plate;

Figure 9 is a detail side elevation of a switch member;

Figure 10 is an elevation of the face thereof;

Figure 11 is a top plan of a spring contact;

Figure 12 is a longitudinal section through the same;

Figure 13 is a plan of a lamp socket blank;

Figure 14 is a diagram of the instrument board and tail lamp circuits; and

Figure 15 is a bottom plan of the assembled switch and steering wheel.

Like numerals refer to like parts in the several figures of the drawings—

This invention is particularly designed for the control of electric circuits upon motor vehicles and is therefore illustrated as mounted upon a part thereof for the most convenient manipulation by the operator. The numeral 10 designates a steering post provided with the usual operating wheel 11 and supporting a clamping block 12 slidably adjustable thereon. This block is formed with a recess 13 in which a gripping block 14 is disposed and provided with a segmental face 15 to engage the post. This block 12 is also formed with an extension 16 through which a set screw 17 is threaded to engage and retain the gripping block in position. This extension also supports one end of the horizontally disposed tube 18, the opposite end of which is mounted upon a boss 19 from the switch casing or frame 20. The tube is secured to these parts in any desired manner, for instance by brazing, and carries the electric cable 21 extending to the casing.

The frame casing 20 being the secured member supports the non-conducting fuse 110 and contact holder 22, and has pivotally mounted thereon at 23, the outer case or

shell 24 carrying the switch and locking mechanisms. The casing 20 is provided with a series of posts 25 about which a circumferential insulating ring 26 is disposed to form an annular wiring chamber 27 from which connections are made with the terminals 28 of the spring contacts 29 upon the outer face of the holder. An improved form of such contact is herein disclosed and 5 comprises a plate 30 bent at its opposite ends 31 and 32 into different planes and provided intermediate thereof with a slot 33 from which the metal is turned at an angle to form a pivot 34 upon which the plate 10 rocks. The end 31 is formed with the usual curved contact point or face 35 and the end 32 apertured at 36 to receive a post 37 from the terminal 28. This post is surrounded by a spring 38 disposed between 15 the head thereof and the end 32 of the plate. By this structure the use of a spring plate is obviated and the objection of loss of elasticity thereof avoided, while the resilient contact is provided by a coiled 20 spring which gives much more efficient and reliable service. These contacts are disposed upon the holder in suitably arranged groups to cooperate with the switch members. The holder is also provided with 25 the usual fuse clips 39 adapted to support the fuses 40 for each circuit. The wiring connections are generally indicated in Figure 2, but are not herein specifically described.

30 The light control switch lever 45 is mounted in a bearing 46 formed on the outer case 24 and has a bearing portion upon its shaft 47 for this purpose. Within the case this shaft has non-rotatably mounted thereon a metal retaining segment 48 and a non-conducting plate 49 which carries the conducting strips or plates 50. These strips are secured by extending their ends through the fiber plate 49, and in order to 35 prevent such ends contacting with the segment 48, the latter is formed with a series of apertures 41 disposed to aline with the ends of the strips. The segment and plate are removably retained on the shaft by a nut 51 bearing against a washer 52. The lower edge of the segment is formed with teeth 53 forming seats to cooperate with a yielding detent 54 having a tapering head to 40 frictionally retain the switch in its different shifted positions. In order that the shift between some positions may be accomplished with less resistance than others, the side walls of the teeth are inclined at different degrees or angles, the walls 55 of 45 the central tooth being at a greater angle than the walls 56 of the outer teeth. This permits the shifting of the head and tail lights from their full light position to a dim light position, or vice versa, with the minimum of 50 resistance to the finger of the operator.

When the shift is to be for full side, head and tail lights, or all lights cut off, the resistance to such movement is increased so that the operator is warned and accidental shifting to such positions prevented. The 55 minimum resistance is offered to first position shift to either right or left, while the maximum resistance occurs during further shift in either direction. The construction of the light control switch is substantially duplicated in the auxiliary switches 57 and 58 disposed at opposite sides thereof to control any other desired circuits and to cooperate with a unitary locking mechanism to be hereinafter described. The operating levers 59 for the auxiliary switches are preferably disposed downward, while the lever 45 of the light switch extends upward to a position directly beneath or adjacent the hand hold of the steering wheel so that 60 it may be conveniently operated by a finger of the hand of the driver grasping the wheel, as fully set forth in my application filed September 16, 1920, Serial No. 410,729.

65 The horn operating bail or arm 60 is pivoted at 61 upon the case 24 and the horizontal portion 62 thereof is longitudinally curved in substantially the same arc as the rim of the steering wheel so as to present an extended area conveniently accessible to the fingers of the hand of the operator as the wheel is shifted for ordinary driving positions. This arm is normally held away from the casing by the spring 63 disposed at the pivots thereof. The arm 68 is provided at one end with a tail piece 64 which bears against a horn lever 65 of non-conducting material pivoted upon a bracket 66 at the inner face of the case. The opposite end of the lever engages a contact 70 spring 67 which cooperates with a terminal 68 to establish circuit to the horn. The lever is moved to its closed position by a spring 69 but is normally held against the tension of this spring by the greater tension of the springs upon the horn arm. When the yoke of the arm is moved toward the case this latter tension is removed and the spring 69 shifts the horn lever to 75 establish circuit. Such construction leaves 80 the arm always free for operation and prevents damage to the more delicate parts of the contact device.

85 Means are provided for locking the casing, all switches, and the horn arm and for 120 the adjustment of such means to permit independent operation of the light switch or horn arm while the remaining members are locked in position. This may be accomplished by a locking plate 70 having a plurality of locking faces and mounted for oscillation upon a disk 71 carried by a lock member 72 secured to the casing 24. The plate is provided with overturned lugs 73 which pass through recesses 74 at the 125

periphery of the disk and, when the plate is slightly rotated, embrace the edge of the disk. The plate is also formed with a central opening 75 having a series of spaced 5 projections 76 to cooperate with stop pins 77 mounted upon the disk. One of the pins 77 is yieldingly mounted as at 78 to permit, when depressed, sufficient rotary movement of the plate for its removal from the 10 disk for the purpose of adjustment for different locking conditions.

The locking plate is actuated by a head 79 upon the rotatable lock cylinder 80 disposed eccentrically to the opening 75, and 15 this head carries a finger 81 which in its travel engages one of the projections 76. The plate is also provided at its periphery with tongues 82 which engage beneath the heads 83 of the posts 25 to lock the casing 20 members together when in closed position, 20 as in Figures 1 and 4. The plate is also formed with a series of apertures 84 which, when the parts are in unlocked position, align with the detents 54 for the several 25 switches, as shown in Figure 1. These detents are disposed in sockets 85 in the lock casing and projected toward the switches by springs 86, while their shanks 87 extend through the disk 71. When the shank is in 30 alignment with an aperture 84 the detent can freely yield to permit operation of the switches, and if the lock plate be shifted to bring a solid portion over this detent shank such movement is prevented. The plate is 35 further provided upon its rear face with a series of conical seats 88 which cooperate with a corresponding tapered head upon a lock pin 89 for the horn lever 65. When this pin is seated, as in Figure 1, this lever 40 is free to close circuit for the horn, but if the plate is shifted to lock, the pin rides out of its seat and is forced into the path of the horn lever to prevent sufficient movement thereof to close circuit.

45 For the purpose of leaving the switch used for the lights, operable when the other parts are locked, the locking plate is formed with openings 90 and 91 therethrough which are disposed to register with the detent for 50 this switch when the remaining faces of the plate are in locking position. When the opening 90 is so aligned the detent is free to retract from the switch and permit its operation, but the body of the plate forces the 55 horn lever into position to prevent contact by the latter, as in Figure 5. If the opening 91 be so aligned a similar operation occurs, except that the lock pin rests in one of the 60 seats 88 and both lights and horn may be operated while the other elements of the switch and casing are locked. A further adjustment of the plate prevents retraction of all 65 of the switch detents but leaves the lock pin seated so that the horn may be operated while the remaining parts are locked. The

plate may be provided with suitable indications thereon to guide the positioning thereof relative to the stop pins for the several locking functions, and by depressing one of these pins the plate may be turned sufficiently for removal and readjustment upon its supporting disk.

The frame casing 20 is suitably recessed to receive an instrument board or dash lamp 94 mounted to engage at its base with the 75 spring contacts 95 upon an insulating support 96. These contacts are pivotally mounted similar to the contacts 29 and connected in series by lines 97 with the usual tail lamp 98 so that the dash lamp indicates 80 the light condition of the tail lamp in the ordinary manner. The lines 97 are also connected with a resistance 99 having a line 100 to one contact terminal 101. The opposite side of the resistance is connected by a line 85 102 to a terminal 103 disposed to be engaged by the end of one of the contacts. When the dash lamp is in operative position, 90 as in Figure 14, the resistance is cut out of the circuit, but when the dash lamp is extinguished or removed for use at the tail lamp, the contact establishes circuit through the resistance to compensate for the dash lamp and the tail lamp circuit is always in operable condition.

The socket 104 for the dash lamp is preferably formed of a blank, as shown in Figure 13, which has a crimped or serrated portion 105 near one end and is slotted longitudinally to form a series of fingers 106 which are 100 bent outward parallel to the body to form an elastic holder for the usual shield 107. This blank is bent into tubular form and the ends of the fingers deflected laterally at 108 to provide a stop to limit the inward movement of the shield, while the opposite end of the socket is also bent laterally at 109 for attachment to the casing. An operating arm 110 for oscillating the socket is secured thereto by being forced over the crimped 110 portion and forms means by which the dash lamp may be conveniently manipulated.

The operation of the several parts will be apparent from the foregoing description and it will be seen that the adjustable locking plate is adapted for a plurality of different locking conditions. With the parts in the position shown by Figure 1 all are released for ordinary operation, while when the plate is shifted to the position shown 115 in Figure 4 all parts are locked. Under some municipal regulations it is required that the light control switch be left free for operation when the remaining parts are locked, and this condition is provided when 120 the plate is adjusted to the position shown by Figure 5. Other regulations require that all parts be locked except the horn which is accomplished by a shift to the position shown in Figure 6. By further ad- 125 130

justment as described, both the lights and horn are released while the other parts are locked. In all of the locking positions the parts of the casing are securely locked and access to the interior thereof or to the clamp upon the steering post prevented. The concealed construction of this clamp avoids tampering therewith, and the casing being formed of pivoted separable members permits convenient access for inspection or repair. The pivoted switch is yieldingly retained in position for shifting against varied resistance by a finger of the hand of the operator when resting on the steering wheel, and such increased resistance warns against accidental shifting beyond the normal positions of use. The spring controlled contact obviates the use of a spring plate and avails the advantages of a coiled tension spring which provides more efficient results. The horn arm is positioned relative to the wheel rim so as to be always readily accessible, while the use of the lever actuated by an independent spring for effecting contact, prevents the transmission of any pressure from the arm to the contact members. The means for locking the horn lever provides for a unitary control of all parts by a single member which is adjustable to effect a plurality of different functions. The mounting for the dash lamp and its circuit connections through a resistance with the tail lamp provide a most desirable construction in which the dash lamp may be extinguished or removed without affecting the tail lamp circuit. This is particularly convenient when it is desired to use the dash lamp to replace a disabled tail lamp.

40 The invention presents a simple, efficient and economically manufactured construction, and while the specific features thereof have been shown and described, still changes and alterations may be made therein as the invention is not confined to such details as set forth in the following claims.

What I claim is:—

1. In a circuit switch, a casing, a plurality of separately operable switch members mounted therein, and a locking device cooperating with said members and having adjustable means to selectively lock all thereof or to leave one or more members free for operation while locking the remaining members.
2. In a circuit switch, a casing comprising separable parts, a switch member mounted therein, and a unitary locking device constructed to lock said member and said casing in closed position and adjustable to permit operation of said member independent of the casing lock.
3. In a circuit switch, a casing, a plurality of contact members mounted therein, holding devices for said members, and a

locking mechanism comprising an adjustable member to lock all of said devices or one or more at will.

4. In a circuit switch, a casing, a plurality of contact members mounted therein, holding detents for said members and an adjustably mounted locking plate cooperating with said detents and constructed to permit independent operation of one or more thereof while retaining the remainder in locked position. 75

5. In a circuit switch, a casing, a plurality of contact members mounted therein, holding detents for said members, and a locking plate cooperating with said detents and having apertures adapted to be alined therewith to permit selective releasing movement of one or more of the detents. 80

6. In a circuit switch, a casing, a plurality of contact members mounted therein, holding detents for said members, and a locking plate having apertures adapted to aline with all of said detents and an independent opening adapted to aline with one thereof to permit its operation while the remaining detents are locked by said plate. 85

7. In a circuit switch, a casing comprising separable members, a plurality of contact members mounted therein, holding detents for said members, a locking plate cooperating with said contact members and having apertures adapted to aline with said detents, and a peripheral lug on said plate to lock the casing members. 95

8. In a circuit switch, a casing, a switch member therein, a sliding device having one end disposed for locking said member, and a locking plate having recesses in which the opposite end of said device is adapted to seat when unlocked. 100

9. In a circuit switch, a casing, a switch member therein, a movable device having one end disposed for locking said member, and a locking plate having means for shifting the opposite end of said device into locking position. 110

10. In a circuit switch, a casing, a switch member therein, a locking pin having one end engaging said member, and a locking plate having a seating recess for the opposite end of said pin with an inclined wall to shift the pin into locking position. 115

11. In a circuit switch, a casing, a movable switch member therein, a locking pin interposed in the path of said member and having a tapering end, and a locking plate having a conical recess to receive the end of said pin when in unlocked position. 120

12. In a circuit switch, a casing, a plurality of contact elements, a movable switch member, a shiftable device for engaging and locking said member, and a locking plate having means to control said elements and independent means to lock or release said member through said device. 125

13. In a circuit switch, a casing comprising separable members, shiftable switch devices mounted upon one member thereof, cooperating contacts upon the opposite member adapted to engage said devices as the casing is closed, a locking device upon one casing member, and fixed locking means upon the opposite member disposed to be engaged by said device when the casing is closed.

14. In a circuit switch, a separable casing, rotatable switch devices mounted upon one member thereof, cooperating contacts upon the opposite member adapted to engage said devices as the casing is closed, means for locking said devices, a locking plate upon one member of the casing controlling said means, and fixed locking posts upon the opposite member to be engaged by said plate.

15. In a circuit switch, a separable casing, switch devices mounted upon one member thereof and having operating handles upon its outer face, cooperating contacts upon the opposite member adapted to engage said devices as the casing is closed, a rotatable locking plate upon one member, and cooperating means upon the opposite member disposed to be engaged by said plate.

16. In a circuit switch, a separable casing, a series of locking posts upon one member thereof, a series of contacts arranged circumferentially of said posts, switch devices upon the opposite member cooperating with said contacts, means for locking said switch devices, and a locking plate upon said opposite member adapted to cooperate with said posts and locking means for the switch devices.

17. In a circuit switch, a pivoted switch member, contacts cooperating therewith, a holding detent for said member, a locking device for said detent and member, and holding seats upon the member having means to vary the frictional resistance of the detent in shifting the switch to different positions.

18. In a circuit switch, a casing, a switch operating member pivoted thereon and having an arm within the casing, a lever having one end disposed in the path of said arm, tension means for normally holding said arm in contact with said end of the lever, a circuit contact disposed in the path of the opposite end of the lever, and means of less tension than the first mentioned tension means for projecting said lever toward said contact when the arm is withdrawn from engagement therewith.

19. In a circuit switch, a casing, a switch operating arm mounted thereon, a lever disposed to be actuated thereby, a circuit contact arranged in the path of said lever, a sliding locking device adapted to limit the

travel of said lever to prevent contact, and a locking mechanism for controlling said device.

20. In a circuit switch, a casing, a switch operating arm mounted thereon, a lever disposed to be actuated thereby, a circuit contact arranged in the path of said lever, a locking device adapted to limit the travel of said lever to prevent contact, a pivoted switch, locking means therefor, and a locking mechanism for controlling said device and switch locking means.

21. In a circuit switch, the combination with a steering post and wheel, of a casing supported laterally from said post, a switch actuating arm mounted upon the casing, and an operating surface upon said arm movable toward and from the wheel axis and disposed adjacent to and beneath the hand hold of the wheel and extended circumferentially thereof.

22. In a circuit switch, the combination with a steering post and wheel, of a casing supported laterally from said post, a switch actuating arm mounted upon the casing, and a curved yoke upon said arm movable toward and from the wheel axis and disposed adjacent to and beneath the hand hold of the wheel and extended circumferentially thereof.

23. In a circuit switch, the combination with a steering post and wheel, of a casing supported laterally from said post, a switch actuating arm mounted upon the casing, a curved yoke upon said arm movable toward and from the wheel axis and disposed adjacent to and beneath the hand hold of the wheel and extended circumferentially thereof, and a vertical switch lever disposed substantially centrally of said yoke and directly beneath said hand hold.

24. In a circuit switch, a separable casing, a pivoted switch member mounted therein, a holding detent for said member, a switch arm mounted upon the casing, a circuit contact controlled by said arm, and a locking plate having an aperture to cooperate with said detent and recesses upon its rear face to actuate locking means for said circuit contact.

25. In a circuit switch, a separable casing having one member provided with fixed locking means, a pivoted switch member mounted therein, a holding detent for said member, a switch arm mounted upon the casing, a circuit contact controlled thereby, a locking plate having an aperture to receive said detent and a recess to actuate locking means for said circuit contact, and lugs upon the periphery of said plate to engage the fixed locking means upon the opposite member.

26. In a circuit switch, a casing, a lock mechanism mounted therein, a supporting disk secured thereto, a locking plate having

a central aperture and inwardly projecting finger, an eccentrically disposed head upon a rotating member of said mechanism having means to engage said finger, and means controlled by said plate for locking a switch member.

27. In a circuit switch, a casing, a lock mechanism mounted therein, a supporting disk secured thereto and having recesses upon its periphery, a removable locking plate mounted upon said disk and having overturned lips to embrace the periphery thereof, means from said mechanism for actuating said plate, and means controlled by said plate for locking a switch member.

28. In a circuit switch, a casing, a lock mechanism mounted therein, a disk secured thereto, a rotatable locking plate supported upon said disk and provided with a central aperture, stop pins carried by said disk, a projection from said plate at its aperture and disposed between said pins, lock controlled means disposed for actuating the plate at the aperture therein, and means controlled by said plate for locking a switch member.

29. In a circuit switch, a casing, a lock mechanism mounted therein, a disk secured thereto, a rotatable locking plate removably supported upon said disk, stop pins carried by said disk one of which is yieldingly projected, a projection from said plate disposed between said pins, means controlled by said mechanism for actuating the plate, and means controlled by said plate for locking a switch member.

30. In a circuit switch, a separable casing having locking means, a pivoted switch member mounted therein, locking means for

said member, a contact carried by the casing, a locking mechanism, and an adjustable locking plate actuated thereby and having a series of faces adapted to jointly or independently lock the before mentioned members.

31. In a circuit switch, a casing, a lock frame mounted thereon and having a rotatable actuating member, a pivoted switch upon the casing, means for holding said switch yieldingly mounted upon the lock frame, a supporting disk upon said frame, and a locking plate movable mounted upon said disk and cooperating with said holding means.

32. In a circuit switch, a casing, a lock frame mounted thereon and having a rotatable actuating member, a pivoted switch upon the casing, a detent for holding said switch yieldingly mounted upon the lock frame, a contact lever, a lock pin therefor mounted in said frame, a supporting disk upon the frame, and a locking plate carried by said disk and cooperating with said detent and pin.

33. In a circuit switch, a separable casing, a lock frame mounted upon one member thereof and having a rotatable member, a pivoted switch upon the casing, a detent for holding said switch yieldingly mounted upon the lock frame, a contact lever, a lock pin therefor slidingly mounted in said frame, a locking post upon an opposite casing member, a supporting disk upon the lock frame, and a locking plate carried by said disk and cooperating with said detent, pin and post.

In testimony whereof I affix my signature.
WALTER J. SPIRO.
